UNITED STATES PATENT OFFICE.

CHARLES P. MADSEN, OF CHICAGO, ILLINOIS, ASSIGNOR TO PELOUZE ELECTRIC HEATER CO., OF CHICAGO, ILLINOIS, A CORPORATION OF ILLINOIS.

ELECTRIC HEATER.

1,007,125.

Specification of Letters Patent. Patented Oct. 31, 1911.

Application filed July 9, 1910. Serial No. 571,235.

To all whom it may concern:

Be it known that I, CHARLES P. MADSEN, a citizen of the United States, and resident of Chicago, Cook county, Illinois, have invented certain new and useful Improvements in Electric Heaters, of which the following is a full, true, clear, and exact description, such as will enable others skilled in the art to which it appertains to make 10 and use the same.

My invention relates to that class of electrically heated devices known as bread toasters, meat broilers, air warmers and the like.

15 The object of my invention is to provide an electric heating device of this character in which the heat generated by the heating element will be imparted or transmitted to the object or material to be heated radiantly 20 through the atmosphere surrounding and containing the heating element, and in which the heat imparted will be confined upon an area where it will be most effective and will not become dissipated in other parts of the 25 device, thereby increasing the effective heating capacity and the heating speed of the heater for a given current consumption.

A further object of my invention contemplates the provision of an electric heater 30 having a heating element or heat generator which will be independent of its containing case or receptacle and removable therefrom as a unit, and which will be comparatively inexpensive to manufacture whereby the 35 heating element may be conveniently removed and renewed at slight cost by the user of the device, should it become damaged or injured in any manner.

Further and more particular objects of 40 my invention are to provide a heater which will be compact and neat in appearance; which will be portable and which will have means for quickly and effectively making and breaking electrical connection with the 45 heating element; and which will be particularly adapted for toasting bread and for broiling or frying meats and other food products.

I will explain my invention further by reference to the accompanying drawings in 50 which: Figure 1 is a top plan view of an electric heater structure embodying my invention; Fig. 2 is a longitudinal sectional view on line 2—2 of Fig. 1; Fig. 3 is a view 55 in side elevation showing an invertible pan

or tray used in conjunction with my electric heater for rendering it adaptable for frying meats, griddle cakes and other food products; Fig. 4 is a view in end elevation showing the plug socket and the terminals for 60 the heating element; Fig. 5 is a view in section on line 5—5 of Fig. 1; Fig. 6 is a top plan view of the unit heating element removed from its containing casing or receptacle; Fig. 7 is a view of the under side of 65 said heating element showing the connecting plug in relative position; Fig. 8 is an enlarged, transverse, sectional view showing the relation of the food grid, the heating element and the heat reflector; Figs. 9 and 70 10 are enlarged detail sectional views showing the means of securing the food-grid and the unit heating element in position; and Figs. 11, 12, 13 and 14 are detail views of the connection plug for connecting the 75 heater to an electric circuit.

I have discovered by extensive experiment that, in a certain class of heaters, if the heating element is maintained out of mechanical contact with the object or material to 80 be heated and with any other object and instead is arranged so that it imparts its generated heat to the object or material to be heated by radiation through the medium of the atmosphere surrounding the heating element, the efficiency and effective heating capacity of the heating element will be greatly increased for a given current consumption. 85 The difficulties which are presented in a heating device of this sort lie in arranging the heating element so that it will impart or transmit all of its generated heat to the external object, and preventing the loss or dissipation of heat at points where it will not be effective in heating the external object or material. I have discovered that the highest efficiency, the most effective heating capacity and the maximum heating speed can be attained by disposing the external object to be heated at a given distance 90 from a heating element of a given temperature. I have accordingly provided an electric heater having a heating element which is arranged to lie in one plane and by arranging the heating element in this manner it may be spaced at a given distance 95 from the external object, the distance being uniform at all points throughout the heated area. The heating element, however, being disposed in one plane radiates heat there- 100 105 110

from on both sides thereof, and in a practical structure it is preferable that the external object or material to be heated be disposed on one side of the heating element. 5 To prevent the heat radiated from the heating element on the other side thereof from being dissipated into the atmosphere or the supporting structure and thereby being wasted so far as the external object is concerned, I have provided a heat reflecting device disposed in a plane substantially parallel with the plane of the heating element and spaced therefrom at a given distance. 10 This device reflects the heat radiated from the unused side of the heating element and cumulatively adds it to the heat radiated from the side of the heating element on which the external object is disposed. In this manner substantially all of the heat 15 generated by the heating element is confined over an area where it is completely effective to heat the external object.

The electric heater which I have shown in the drawings and in which my invention is embodied, is especially adapted for toasting bread or for broiling meats. I have found by experiment that the most effective heating capacity and the highest efficiency are obtained by disposing the food product to be 20 heated, the heating element and the reflector in parallel planes and by spacing the food products at about one-half the distance from the heating element as the heat reflector is spaced therefrom. These proportions may 25 vary within the range of one to one and one to two without material detriment to the efficiency of the device. In this structure the heating element preferably comprises an electrical conductor 1 of suitable resistance 30 to produce the desired temperature with a given quantity of current and of suitable characteristics to withstand the temperature to which it is subjected without fusing or without deteriorating. The conductor is 35 preferably a round wire for the reason that it is the least expensive, but it will be understood, however, that a wire or rod of any desired cross section may be used. This conductor is preferably wound in a reflex or 40 zigzag manner and is disposed in one plane. It is retained in position by a base member of refractory insulating material 2 through the medium of L-shaped spring members 3 disposed in parallel rows on each side of the 45 flanges 4 carried on the edges of said base member. One of these L-shaped springs is preferably provided for each bend or bight in the conductor 1. They are anchored at the lower edges 5 of the outer face of the 50 flanges 4 and extend vertically for a distance adjacent the outer faces of the flanges and then horizontally through suitable slots 6 provided in the upper edges of said flanges. At the inner ends of these springs 65 are hooks 7 into which the conductor 1 is

looped. These springs automatically compensate for the expansion and contraction of the conductor 1 due to changes in temperature thereof and thereby maintain the several portions of wire taut at all times so 70 that they will not become displaced out of a horizontal plane. By arranging the springs in this manner they are protected by the flanges 4 so that they lie almost wholly outside of the influence of the heat and in consequence their temper will not be impaired. The conductor 1, in the structure shown, is wound to form a rectangle but, of course, it may be wound or otherwise arranged in a single plane of any geometric figure. Furthermore the tension members or openings may be disposed in any suitable relation to the conductor to maintain it in its given plane. Of course if a conductor of sufficient rigidity to be self-maintaining were 85 used, the tension members may be dispensed with.

The insulating base 2 is supported in the proper horizontal position within a suitable containing case or receptacle 10 by means of 90 two plates 11 secured to the bottom of the receptacle 10 and extending vertically upward. The upper edges of these plates lie adjacent the shoulders 12 on the underside of the base member and are intended to prevent 95 said base member from shifting laterally. The base member is clamped securely in position on the upper edges of these plates by the bolts 13, which also clamp the food grid in position, as will be hereinafter described. 100 The space below the insulating base is preferably filled with magnesia or some other loose, refractory heat insulating material (as shown in Figs. 2 and 5) to prevent the heat from reaching the casing and rendering it 105 too hot for comfortable handling. It will be noted that the heating conductor and the insulating support thereof comprise a unit heating element structure which is independent from the casing and the rest of the 110 apparatus and which is easily removable therefrom. This is a desirable feature, since the heating element can be manufactured comparatively cheap, and in the event that it should become burned out or otherwise 115 damaged it can be conveniently removed from the receptacle and a new unit substituted at a slight cost. This unit heating element is insulated from the rest of the apparatus and the base thereof is in metallic 120 contact with the casing receptacle only at its points of support at the upper edges of the supporting plates 11. It is thus separate from the casing by an air space, consequently 125 an almost negligible quantity of the heat generated by the heating element will be dissipated in the casing.

Disposed upon the upper face of the insulating base 2, and lying substantially parallel with the plane of the heating ele- 130

ment, is the heat reflector 15. This preferably comprises a flat, rectangular, metallic plate loosely slidable in side grooves formed by overhanging portions 16 of the flanges 4 on the insulating base. One end of this reflector projects through a slot 17 in the end of the casing and has an upturned flange which substantially closes said opening and which carries a small knob or handle 18 by which the reflector may be conveniently removed or placed in position. The heat reflector serves the additional purpose of a removable crumb tray or dripping tray.

The casing or receptacle 10 is open at its top. Spanning this opening and disposed at a given relative distance above the heating element and in a parallel plane thereto is the food holder or food grid. This grid is a flat, open-work structure comprising a rim 20 fitting the upper edge of the casing and having a number of bars or rods 21 spaced apart and arranged transversely of said rim. The rods are secured to a depending flange 22 so that they will lie substantially flush with the upper face of the rim 20. The food grid thus presents a substantially flat food-supporting surface upon which bread, meat or other food products may be laid. One end of this flange is continued downward to a point very close to the bottom of the receptacle and serves not only to assist in spacing the insulating base from the end thereof, but it also serves to prevent food crumbs or grease drippings from falling into the lower part of the receptacle. As before mentioned, the food grid is clamped in position by the bolts 13 which pass through the lugs 24. The structure which I have just described is particularly designed as a bread toaster and will conveniently accommodate two slices of bread. The heating element is in a sense divided into two divisions and each division is substantially covered by a slice of bread. One of the reflex portions of the conductor is omitted to provide a gap between these two divisions, this being left in order that the temperature will not become too great at the center of the device and scorch the adjacent edges of the two slices of bread. The upper faces 25 of the flanges are arranged to diverge or flare outwardly so as to increase the heat area of the device. It is desirable, though not necessary, in the use of this device that the object or article to be heated cover substantially the entire heated area since it is evident that all of the heat generated by the heating element will then be utilized. The casing or receptacle 10 is preferably formed up from sheet metal and is made to present a neat appearance. It is provided with suitable legs 10' and with handles 20' on the ends by which it can be conveniently carried from place to place.

65 Referring now to Fig. 3 I have shown a

tray or pan 27 having a handle 28 on each end and having a flat bottom which covers the entire upper area of the receptacle. This pan may be used in two positions, (as will be seen by the full and dotted lines in 70 said figure) either as a fry pan, when it is in its normal position with its sides upturned, or as a griddle plate when in an inverted position.

Depending from the under face of the 75 insulating base 2, near one end thereof, is a block of insulating material 30 to which are secured two plates 31 serving as terminals for the heating element, the ends of the conductor 1 being connected by suitable 80 leads 32 lying on the under face of the insulating base and extending to the terminal plates 31. These terminal plates 31 extend through the opening in the bottom of the casing 10 and lie within a plug socket or receptacle 33 which is secured to the bottom of the casing 10 and which has lateral guide flanges 34 to maintain the connecting plug in connection with the terminal plates 31. The connecting plug is composed of two 85 parts 35 of insulating material clamped together by bolts 36 and having registering depressions 37 in their adjacent faces in which depressions the contact terminals 38 are arranged, their binding posts 39 being 90 inclosed between the two parts of the plug. The forward end of this plug is provided with two slots 40 which permit the terminal plates 31 to enter and make contact with the contact terminals 38 of the plug, and 95 the rear end of the plug is provided with a single opening 41 through which the electric conductors 42, representing the source of electric current, enter the plug. Surrounding these conductors 42 is a spiral 100 spring 43, anchored at one of its ends 44 to the plug and freely extensible along the conductors in a direction away from the plug. This spring has secured to it about midway of its length a suitable knob 45. 105 The purpose of this arrangement is to permit the plug to be removed from its socket and the circuit to be quickly broken in order to prevent undue burning of the contacts. The plug, as will be noticed, is inserted almost wholly within its socket and is held therein by friction. When it is desired to disconnect the heater from the source of current the spring 43 is extended by pulling upon the knob 45. This places 110 a tension upon the plug and as soon as this tension overcomes the friction between the plug and its socket the plug will fly out of its socket with a quick movement and the circuit will be quickly broken thereby preventing to a great extent the burning of contacts.

My novel heater as herein shown and described is capable of considerable modification without departing from the spirit of 115

my invention. For example, it is obvious that windings of the conductor may be permanently secured at one side of the insulating base and held in tension by a single movable element or comb at the other side of the base. It will also be understood that the heating elements may be arranged either singly or in pairs and supported in inclined or vertical positions and the means 5 for supporting and protecting the heating element may be modified according to the uses to which the device is to be put. Still other modifications may be made and employed within the scope of my invention, 10 and for the reasons here stated I desire it to be understood that my invention is not limited or confined to the specific structure herein shown and described.

I claim:

20 1. In an electrical heater a heating element comprising a non-insulated electrical conductor openly wound to lie in one plane, an insulating support therefor adapted to maintain said heating element in said plane, 25 a flat heat reflector plate removably placed upon said insulating support in parallel relation to and at a fixed predetermined distance from said heating element, a food holding grid for maintaining an article to be heated 30 in parallel relation to the opposite side of said heating element and at a given distance therefrom, and a container case removably holding said parts in their relative position, and having an opening in one end 35 for permitting the removal of the reflector plate.

2. In an electrical heater a heating element comprising a non-insulated electrical conductor reflexively wound to lie in one 40 plane, an insulating base plate, up-standing flanges on the side edges of said base, compensating springs upstanding from said base and passing through said flanges for maintaining said heating element in said 45 plane, a heat reflector carried by said insulating support in parallel relation to and at a given distance from said heating element, and an openwork grid for maintaining an article to be heated in parallel relation to the opposite side of said heating 50 element and at a given distance therefrom, said parts coöperating to confine the effective heat substantially on the side of said element adjacent the article to be heated.

55 3. In an electrical heating device a suitable casing, an insulating base supported therein and having upstanding flanges, and a non-insulated heating conductor wound to lie in a single plane, said base and conductor constituting a removable heater unit, and temperature compensating spring 60 extending through said flanges for supporting said conductor in its given plane regardless of the contraction and expansion of said

electrical conductor due to variations in 65 temperature thereof.

4. In an electrical heating device a suitable casing, an insulating base supported therein and having upstanding barrier flanges, and a non-insulated heating conductor wound to lie in a single plane, and said base and conductor constituting a removable heater unit, and temperature compensating springs extending through said flanges and connected to said conductor for 70 holding said conductor in its given plane regardless of the contraction and expansion of said electrical conductor due to variations in temperature thereof, and a metallic plate, 75 heat reflector removably supported by said insulating base in parallel relation to and at a given distance from said heating conductor.

5. In an electrical heating device a suitable casing, an insulating base supported 85 therein, a heating element comprising an electrical conductor arranged in a single plane, individual protected compensating devices carried upon said insulating support and connected to different parts of said heating 90 element for maintaining said heating element in its given plane regardless of the contraction and expansion of said electrical conductor due to variations in temperature thereof, heat insulating barriers interposed between said 95 individual compensating devices and said conductor, a heat reflector plate supported by said insulating base in parallel relation to and at a given distance from one side of said heating element, and a food grid supported by said casing parallel to and at a given distance from the side opposite to the 100 heat reflector.

6. An electrical heater comprising a casing or receptacle open at its top, an insulating base member supported within said casing adjacent the open top thereof, a relatively thin heating element comprising an electrical conductor wound in one plane, a plurality of protected spring tensioning devices carried upon said insulating base and connected to different points of said heating element for taking up the slack due to the expansion of said electrical conductor, and slotted heat insulating barriers on said base 110 through which said tensioning devices pass, said base and heating element constituting a heater unit dechable from said receptacle, a heat reflector plate removably mounted on said insulating base in parallel relation 115 to and at a given distance below said heating element, and a food grid spanning the open top of said receptacle and lying parallel to and at a given distance above said heating element.

7. In an electrical toaster the combination with a suitably formed receptacle, an insulating base member supported within 120

- said receptacle, a non-confined heating element comprising an electrical conductor reflexively laid in one plane, a plurality of yielding L-shaped spring members extending through said base member and individually connected to said electrical conductor at the bends therein for maintaining said heating element in its given plane irrespective of the contraction and expansion of said electrical conductor, said insulating base and said heating element being removable as a unit from said receptacle, a food grid supported by said receptacle parallel to and at a given distance above said heating element, and a heat reflector supported on said insulating base at not more than twice said given distance below said heating element. 65
- 5 8. In an electrical heating device the combination with a suitable receptacle, an insulating base having side barriers, and a heating conductor carried thereby together comprising a removable heater unit, and a plurality of spring members disposed behind said barriers and connected to different points of said heating element for constantly maintaining it in a single plane irrespective of the contraction and expansion thereof, said spring members being protected by said barriers from the influence of said heating element. 70
- 20 9. In an electrical heater the combination with a suitable receptacle open at its top, an insulating base member and a thin, openly wound, electrical heating element carried thereby, plates upstanding from the bottom of said receptacle supporting said base upon their edges within said receptacle but out of contact with the walls thereof and adjacent to said open top, said parts being removable from said receptacle as a unit, a heat reflector plate carried upon said base member below said heating element, and a separable food grid spanning the opening in said receptacle and arranged above said heating element, all of said parts cooperating to render cumulatively effective on the food grid side of said heating element substantially all of the heat radiated from both sides of said heating element. 75
- 25 10. In an electrical heater the combination with a suitable receptacle, of an insulating base member contained within said receptacle, upwardly directed flanges on opposite sides of said base member, transverse slots in said flanges, a plurality of L-shaped spring hooks supported on the outer faces of said flanges and having a portion extending through said slots, and an electrical heating conductor reflexively wound in a single plane and being supported at the bend in each reflex by said spring hooks, said spring hooks serving to maintain said elec- 80
- 30 trical conductor in its given plane irrespective of the contraction and expansion thereof. 85
- 35 11. In an electrical heating device the combination with a receptacle, of a unitary heating element removably mounted within said receptacle, said heating element comprising an insulating base and an electrical conductor doubled back upon itself a plurality of times and disposed in a single plane, and upstanding yielding spring devices on said base member for individually supporting said conductor at the bends therein, and barriers on said base for protecting said springs from the heating influence of said conductor. 90
- 40 12. In an electrical heating device the combination with a receptacle, of a unitary heating element removably mounted within said receptacle, said heating element comprising an insulating base and an electrical conductor doubled back upon itself a plurality of times and disposed in a single plane, and upstanding yielding spring devices on said base member for individually supporting said conductor at the bends therein, a heat protecting barrier interposed between said devices and said conductor, a heat reflecting plate carried upon said base member below said heating conductor and a food grid supported by said receptacle 95 above said heating element, said heating element, heat reflector and food-grid being disposed in parallel relation, and at a given distance from each other. 100
- 45 13. In an electrical toaster the combination with a suitable casing having an opening in its bottom and a unitary heating element comprising a refractory insulating base member and a non-confined, openly wound electrical conductor supported thereby in one plane, said heating element being removable from said casing, a block of insulating material mounted upon and depending from said base member, terminals carried by said block and projecting through the opening in said casing, a plug socket depending from said casing adjacent the opening therein and a connection plug removably retained in said socket in contact with said terminals. 105
- 50 14. In an electric heater the combination with a casing, and a heating unit disposed within said casing and comprising an insulating base and a non-insulated, openly wound, electrical heating conductor supported thereby and arranged in one plane entirely out of contact with said base, said heating unit being separated from said casing by an air space, and loose refractory heat insulating substance substantially filling said space. 110
- 55 15. An electrical heating device comprising a casing having an opening therein, an 115
- 60
- 65
- 70
- 75
- 80
- 85
- 90

insulating base and a heating element carried thereby contained within said casing, terminals for said heating element a column of insulating material carried by said insulating base, supporting said terminals and projecting through the opening in said casing, a plug socket carried by said casing adjacent the opening therein, a detachable connection plug retained in said socket in engagement with said terminals.

16. In an electric toaster a suitably formed casing, a heater unit comprising a body of insulating material and an openly wound single plane heating element above said plate, and means for automatically tensioning said heating element to keep it in its given plane, members upstanding from the bottom of said casing and supporting said heater unit out of contact with said casing so as to leave an air space surrounding said heater unit, and loose heat insulating material substantially filling said space.

17. In an electric toaster a suitably formed casing open at its top, a removable heater unit consisting of a plate of refractory insulating material, a non-insulated conductor openly wound in a single plane parallel to and above said plate, and means on said plate connected to said conductor at different points for keeping it in its given plane, a thin strip upstanding edgewise from the bottom of said casing and supporting said heater unit close to the open top of the casing and out of contact with the casing so as to leave an air space around said heater unit, and loose heat insulating material, such as asbestos and magnesia, substantially filling the space below said heater unit.

18. In an electric toaster a suitably formed casing open at its top, a removable heater unit consisting of a plate of refractory insulating material, a non-insulated conductor openly wound in a single plane parallel to and above said plate, and means on said plate connected to said conductor at different points for keeping it in its given plane, a thin strip upstanding edgewise from the bottom of said casing and supporting said heater unit close to the open top of the casing and out of contact with the casing so as to leave an air space around said heater unit, loose heat-insulating material, substantially filling the space below said heater unit, said casing having an opening in its bottom, and insulated contact

blades depending from said insulating plate through said opening.

19. An electric heater comprising a plate 60 of refractory insulating material, flanges upstanding from the edges of said plate, a conductor wound in a single plane between said flanges, and individual spring tension members upstanding from said plate adjacent the outer faces of said flanges and connected to different points of said conductor for automatically maintaining the individual turns of said conductor in a common plane.

70 20. An electric heater comprising a flat plate of refractory insulating material having upstanding side flanges, a heating conductor wound parallel to and above said plate and in a single plane, openings in said 75 flanges, and a plurality of spring members anchored along the outside of said flanges and passing through said openings into individual connection with the several turns of said conductor for automatically keeping said conductor in its given plane.

21. An electric heater comprising a plate of refractory insulating material, flanges upstanding from the edges of said plate, a conductor wound in a single plane between 85 said flanges, a plurality of spring tension members upstanding from said plate adjacent the outer faces of said flanges and independently connected to different points of said conductor for automatically maintaining 90 said conductor in its given plane, and a separable reflector plate laid upon said plate between said flanges.

22. An electric heater comprising a plate of refractory insulating material, flanges 95 upstanding from the edges of said plate, a conductor wound in a single plane and disposed between said flanges, tension members upstanding from said plate adjacent the outer faces of said flanges and connected to 100 different points of said conductor for automatically maintaining said conductor in its given plane, a block of insulating material depending from said insulating plate, and terminals for said conductor supported 105 by said block.

In testimony whereof, I have hereunto set my hand, this 29th day of June, 1910, in the presence of two subscribing witnesses.

CHARLES P. MADSEN.
